PAGE STORAGE CABINET

Lee K. Williams, Omaha, Nebr.

Application January 7, 1931. Serial No. 507,221

1 Claim. (Cl. 187—36)

Newspaper page chases with the type therein are heavy and are awkward to handle, weighing approximately two hundred pounds each. The chases after being transferred on trucks from the composing room to the stereotype room are manually handled. When not required for immediate use the chases or forms are arranged in racks and any changes in the forms require the removal of the chases from the racks onto the truck. As each chase is arranged on a single truck a large number of trucks are required and the arduous labor of the frequent lifting of the page forms or chases will be appreciated as well as the large number of trucks which are frequently required. A number of trucks necessarily occupy a large floor space and occasion a lack of space in the office which results in general congestion.

The object of this invention is the provision of a newspaper page form or chase storage cabinet for the holding of full size newspaper pages locked in their stereotype chases, in which the cabinet is provided with several compartments, for the reception of a large number of forms or page chases, together with means for automatically causing the raising or lowering of the forms in the cabinet to hold the several forms or page chases in a line with the top of a truck so that the said forms or chases may be readily drawn out of the cabinet and onto the truck or may be readily slid off of the truck into the desired compartment in the cabinet, and whereby a materially less number of trucks are required; more room space is achieved, confusion with respect to the traveling of the trucks and likewise with respect to the arrangement of the proper page forms on the trucks, is obviated and the manual handling or raising or lowering of the chases when moved from the cabinet to the truck or from the truck to the cabinet is entirely overcome.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a front elevation of the improvement.

Figure 2 is a transverse sectional view approximately on the line 2—2 of Figure 1. 60

Figure 3 is a similar sectional view approximately on the line 3—3 of Figure 1.

Figure 4 is a sectional view approximately on the line 4—4 of Figure 3.

Figure 5 is an end view looking toward the 65 lower portion of the device.

Figure 6 is a greatly enlarged sectional view approximately on the line 6—6 of Figure 1.

Figure 7 is a diagrammatic view of the electric 70 wiring and switches.

From a suitable metal base 1 there arises the corner members 2 of the frame of the improvement. The corners are in the nature of angle

elements and are connected at their upper portions with a top member 3 which may be in the 75 nature of a flanged sheet or which may be constructed of angle irons. The corner posts, slightly above the base are connected together by webs or plates 4.

The base has a corner extension which is indicated for distinction by the numeral 5 and on this extension there rests an electric motor 6 which is of the reversible type. The outer end of the shaft of the motor has prefer-

ably fixed thereon a fly wheel, and the inner end of the shaft 7 has a flexible coupling or connec-

80 tion 8 with a driven shaft 9. The driven shaft comprises two parts arranged in suitable bearings and between the said parts of the shaft there are reducing gears which are mounted in a suitable casing 10.

As the reducing gears are of the ordinary construction the same have not been illustrated by the drawings. The shaft 9 has fixed on one of its ends a spur gear 11 that

85 is in mesh with a similar gear 12 fixed on a shaft 13 that is journaled in bearings provided in spaced pedestals 14—14 which are fixedly sup-

90 ported on the base of the frame. What I will term the outer end of the shaft 13 is squared in cross section, as indicated by the numeral 15, 100

and this squared end may be engaged by a socket nut whereby the shaft may be manually turned. The pedestals 14 have depressions that

enter from the upper flat ends thereof, the outer 105 depression having arranged therein Hyatt radial

bearings 16 for the lower and non-threaded por-

110 tions 17 of vertically arranged screws 18. The lower and reduced ends of the non-threaded portions 17 of the screws have their shoulders engaged by Timkin thrust bearings 19. Fixed

on each of the non-threaded portions of the screws 18 there is a mitre gear 20, and the outer face of this mitre or bevel gear rests on a bronze washer 21 supported on the top of each of the 5 pedestals 14. The shaft 13 has its ends journalled on Hyatt radial bearings 22 arranged in transverse round openings in the pedestals 14. Suitable discs or collars 23 hold the bearings in their cages and in the pockets in the pedestals 10 therefore. Fixed on the shaft 13 are mitre or bevel gears 26 which are in mesh with the mitre or bevel gears 20.

The upper ends of the screws 18 are reduced and non-threaded and are engaged by Hyatt 15 roller bearings 27 arranged in raceways provided by sockets 28 that are fixedly secured to the top 3 of the frame.

The inner and transverse flanges of the angle 20 elements providing the corners 2 of the frame have welded or otherwise secured thereon vertically disposed guide plates 29 which are contacted by the angle corner members 30 of the milled shelves 31 of the improvement. The open 25 ends of the shelves 31 are arranged at the front of the cabinet, and the side members of the said shelves have bolted or otherwise fixed thereon nuts 32 through which the screws 18 pass, and which nuts, of course, engage with the threads of the screws. The shelves 31 are equidistantly 30 spaced, and each shelf is of a size to receive therein a tray 33 which is preferably in the nature of a flat but strong plate and which has its outer edge provided with a depending bent portion 34. One of the outer corner posts has a 35 plurality of equidistantly spaced preferably rectangular openings 35 therethrough, the said openings having their lower edges arranged in a plane with the shelves 33 and inward of the openings the said corner post has welded or 40 otherwise secured thereon a vertically disposed bar 36 provided with openings 37, which communicate with the openings 35 and are of the same shape as that of said openings 35. The bar 36, in a line with the openings 37, is bored 45 transversely, the outer walls of the bore, or those communicating with the openings 37, having their walls rounded toward each other to provide seats for metal balls 38 which are forced against their seats by springs 39, the said springs being 50 retained in the bores of the bars 36 by headless threaded plugs 40, the outer faces of the plugs being kerfed.

The said corner post has fixed on its outer 55 face a strip of insulating material which is indicated by the numeral 41 (Figure 6). The strip has fixed thereon a contact element 42 which is normally engaged in a contact of a switch arm 43. The switch arm or contact maker 43 is pivotally secured, as at 44, to a bracket on the insulator strip 41, and the arm 43 is influenced to engage with the contact 42 through the medium of a coil spring 44' which is fixed to the arm and is fixed to the strip. The inner end of the arm 60 43, or the end thereof adjacent to the openings 35 has journaled thereon a roller or may have fixed thereto a cam head 45.

The numeral 46 designates a key member 65 that has a reduced shank 47 provided on one of its edges with a rounded depression 48 and which shank 47 is of a size to be received through the alining openings 35 and 37. The widened outer portion of the key 46 has on its end a lateral extension 49 which is in the path of contact with the head 45 on the arm 43. It will 70 be apparent that when the angle end or finger

49 of the key engages with the roller or cam head 45 of the arm 43, the said arm will be swung on its pivot 44 to bring the same away from the contact 42, and consequently break the circuit between the contact elements.

Reference is now to be had to Figure 7 of the drawings which illustrates the diagram of the electric circuit. It will be noted that the wire leading from the contact on the arm 43 is grounded and that the wire leading from the contact 42 is provided with two branches, each of which is connected to metal plates in the nature of contacts 50 and 51, respectively. Opposite the contacts 50 and 51 there are other contact plates 50' and 51', each of which having a wire leading therefrom to a holding coil 52 and 53, respectively. The coils, when energized attract centrally pivoted metal latch members 54 and 54', respectively, the hooked ends of the said latches being influenced by springs 55, respectively, out of contact with a centrally pivoted plate 56 of insulating material. The plate has its outer face, adjacent to its ends, provided with knobs 57 and 58, respectively, and the plate is normally held in one position through the 100 medium of a centrally fixed arched spring 59 whose arms contact with the inner face of the said plate, and which spring is disposed opposite the pivotal support 59' for the plate. The insulator plate carries on its inner face metal contacts 60 and 60', as well as contacts 61 and 61', the respective pairs of contacts being disposed opposite the pairs of contacts 50' and 51—51', and a pressure on either of the buttons 57 or 58 will swing the plate to bring its contact strip or 105 fingers into engagement with either of the pairs of contacts 50—50' or 51—51' and when the switch element 56 is swung to either of such positions the same will be engaged by one of the holding dogs 54 or 54'. The holding coils 52 and 110 53 are wired to the armature of the motor, the return wires from the armature being connected by branches to the contact strip 60—60', while the contact element 61—61' is wired to the coil 62 for the motor and the return wire from the 115 coil is grounded.

The key 46 is inserted in the opening to stop the elevator comprising the shelves 31 so that any one of the shelves will be moved to a position in line with the top of a truck T so that the page form of chase C can be moved off of the truck onto the desired shelf or removed from the shelf onto the truck. If the elevator is to rise in the frame pressure is exerted against the knob or button 57 which will bring the contact 60—60' against the contacts 50—51, causing the current to flow from the motor through the contact 60' to the contacts 42 and 43. This energizes the holding coil 52, so that the same will attract the latch 54 to bring the hooked 125 end thereof into engagement with the plate 56, thus holding the contacts 60—60' in engagement with the contacts 50—50'. When the elevator rises to bring the shelf in a line with the top of the truck T the finger 49 on the key 46 will 130 be brought into engagement with the head 45 of the switch member 43, swinging the said switch member against the tension of its spring 44 away from the contact 42, thereby breaking the circuit and holding the elevator at a proper position with respect to the top of the truck. The elevator is, of course, raised by the turning of the screws through the nuts 32. This, of course, deenergizes the holding coil 52 and permits of the spring returning the latch 54 to initial position.

sition. When the elevator is to be lowered the second knob or push button 58 is pressed which brings the contacts 61—61' into engagement with the contacts 51—51' so that current will flow to the circuit maker as well as energize the holding coil 53 to cause the latch 54' to lock the insulated plates 56 in a position to hold the contact 61—61' in engagement with the contacts 51—51', and when the finger 49 of the key 46 again engages the head 45 to break the circuit the elevator will be lowered and the desired shelf thereon arranged in a line with the top of the truck T. This permits of the spring 51 returning the insulated plate 56 to initial position.

It is believed the construction, operation and advantages of my invention will be understood and appreciated by those skilled in the art to which such invention relates without further detailed description.

The bent members 34 will be stamped say from 1 to 14 consecutively so that the slides 13 will be consecutively numbered. The device opposite the openings 35 will be likewise numbered. If the page wanted should be on slide 12 then the key plug 49 would be inserted in contact opening marked 12, button switch pressed for raising or lowering the elevator as the case may be and the elevator would stop at the point to

bring the slide 12 in a line with the top of the truck.

Having described the invention, I claim:

In a page storage cabinet for newspapers which includes a frame, an elevator therein, a reversible electric motor for operating the elevator, and an electric circuit for the motor, said elevator having shelves and having spaced openings opposite the shelves, a bar secured in the frame and having openings therethrough aligning with the first-named openings, spring influenced catches partly movable into the openings in the bar, a normally closed electric circuit breaker on one side of the frame and electrically connected in the circuit and includes a fixed contact and a spring influenced pivotally supported contact, a revoluble head on the pivoted contact, a key having a stem insertible through any of the registering openings in the elevator and bar and designed to be engaged by the catch that aligns with such openings, said key having an outer angle end to engage with the head of the pivoted contact for moving the same away from the fixed contact when the elevator is raised or lowered, a hand operated switch electrically connected in the circuit and to the motor to cause the reverse turning of the motor and to operate the elevator in two vertical directions.

LEO K. WILLIAMS.
